TUFTING MACHINE

Glenn Looper, Dalton, Ga.

Application December 15, 1936, Serial No. 116,003

11 Claims. (Cl. 112—79)

This invention relates to tufting machines, and the invention has for an object to provide a machine of this kind to be used in the decoration of articles, such as bedspreads, pillow tops, rugs, dress coats for ladies and other articles of like nature and more particularly when the material to be decorated is of light weight texture, such as thin sheeting.

In tufting machines now generally known and used satisfactory work cannot be done in connection with thin fabric due to the fact that such prior machines lack adequate fine adjustments necessary to satisfactorily accomplish the work results desired and, furthermore, such machines already known are complicated in structure making the same extremely unsatisfactory in producing fine work. It is another object of the invention to provide a machine which obviates disadvantages such as these and produces a machine fully capable of working upon fabric of a thin or light weight texture.

In the general art of tufting is embodied the step of passing through the fabric along predetermined lines or at desired points on the fabric heavy strands, preferably of yarn, said strands being formed into loops which are afterwards severed to produce the desired pile. This insertion or passing of the strands through the material and particularly when the material is light in weight, often results in unsatisfactory work due to the fact that the work being operated upon is not sufficiently heavy to withstand or resist the friction of the strands passing therethrough and especially when such strands are dyed on account of the relatively wide slot in the feed plate. An additional object of the invention is to provide a tufting machine free of such objections.

Another serious problem in connection with a tufting machine is to have a simple means of adjusting the length of the pile and at the same time keeping the looper, cutter and needle as comprised in the tufting machine in proper relative relation to each other so that the looper will loop the thread and the cutter sever the loop with a resultant even pile. An additional object of the invention is to provide a tufting machine which provides for this advantageous result.

The invention also has for an object to provide a machine of this kind wherein the looping and cutting mechanism does not form a part of or is in driving connection with the feeding mechanism for the cloth, thus relieving such feeding mechanism of undue strain as might otherwise affect the work result and particularly such im-

perfections in the work result which might occur upon wear, even though very slight, of any part of the feeding mechanism. If the looper and cutting mechanism constituted a part of the feeding means or was driven directly therefrom, any wear on the part of the feeding mechanism would throw out of adjustment and timing sequence any operation of the looper and cutter with respect to the needle forming the loop.

The invention also contemplates as an object to provide a tufting machine of this kind wherein means are provided for the adequate adjustment of the looper to a very fine point with respect to the needle forming the loop and wherein means are also at hand whereby the looper can be set at whatever desired angle necessary to catch the loop as the loops formed by the needle often vary in size depending upon the character of the strand and more particularly the dye coloring of the strand.

It is also an object of the invention to provide a machine of this kind wherein the cutting means may be properly adjusted with respect to the looper to assure proper cutting of the loops formed around the looper.

The invention has for a still further object to provide means whereby ready and rapid removal and replacement may be had of the cutting means or more particularly the knife comprised in such cutting means so that the same may be sharpened or a new cutting means or blade substituted without throwing any parts of the machine out of adjustment, thus eliminating liability of loss of time in the normal operation of the machine.

The invention consists in the details of construction and in the combination and arrangement of the several parts of my improved tufting machine whereby certain important advantages are attained and the device rendered simpler, less expensive and otherwise more convenient and advantageous for use, as will be hereinafter more fully set forth.

The novel features of my invention will hereinafter be definitely claimed.

In order that my invention may be the better understood, I will now proceed to describe the same with reference to the accompanying drawings, wherein:—

Figure 1 is a somewhat diagrammatic view in front elevation of a tufting machine constructed in accordance with an embodiment of my invention;

Figure 2 is an enlarged fragmentary view partly in section and partly in elevation illustrating certain parts of my improved mechanism as

herein embodied, the line of section being taken in a direction at right angles to the line of travel of the goods to be operated upon;

5 Figure 3 is a fragmentary sectional view taken substantially on the line 3—3 of Figure 2 looking in the direction of the arrow;

10 Figure 4 is a fragmentary view in elevation of the cutting means herein embodied and at the side opposite to that illustrated in Figure 3, portions of the machine as illustrated in Figure 3 being omitted;

15 Figure 5 is a view similar to Figure 3 but showing certain of the parts in a second position and with the looper initially engaging the strand or thread in the production of a loop as the needle retracts;

20 Figure 6 is a sectional view somewhat similar to Figures 3 and 4 but showing certain of the parts in a still further position, said figure also illustrating other details of construction as herein employed;

25 Figure 7 is a fragmentary view partly in section and partly in elevation illustrating in detail certain of the features for operating the cutting means and looper;

Figure 8 is a transverse sectional view taken through the presser foot herein disclosed;

30 Figure 9 is an enlarged fragmentary view in perspective of the looper and its associated plate as herein comprised.

35 My improved invention comprises in its assembly a sewing machine structure of any well known or preferred type including a head H through which operates the needle bar 1 and the presser bar 2 and wherein the head H has underlying the same the bed plate 3. The sewing machine structure also comprises the conventional rock shafts 4 and 5 extending lengthwise of the bed of the machine and fore and aft of the 40 opening 6 in the bed plate 3 which is normally closed by a throat plate 7 upon which bears from above the presser foot 8 carried by the lower or working end portion of the presser bar 2. Coacting in a well known manner with this throat plate 7 from below is the feed dog 9 of a conventional type and which has conventional movement through a slot 10 in the throat plate 7. The throat plate 7 in the present embodiment of the invention does not have a separate opening for 45 the needle N but said needle in its reciprocation has desired movement through the forward end portion of the central slot 10. This central slot 10 is also of material length and is preferably of a length to have its rear end terminate beyond 50 the heel portion of the presser foot 8.

55 The feed dog 9 is carried, as is well known, by the bar 11, one end portion of which is operatively engaged, as at 12, with a rock arm 14 carried by the shaft 4 for substantially reciprocating the bar 11 in a horizontal direction or in a direction substantially parallel to the working face of the bed plate 3. The opposite end portion of the bar 11 is operatively connected, as at 15, with a suitably disposed rock arm 15' carried by the shaft 5 whereby the desired rearward and upward oscillations are imparted to the bar 11 to assure the feed dog 9 having proper contact from below with the work to feed the same rearwardly. The shafts 4 and 5 are rocked in a well known manner at proper relative speeds.

60 It is to be stated at this time that the mechanism for rocking the shafts 4 and 5 and for reciprocating the needle bar 1 may be as preferred, it only being necessary that there be the required timed sequence of operations.

65 The presser foot 8 is relatively broad so as to provide its under surface with relatively large contacting areas for engagement with the material being worked at opposite sides of the slots 10, said areas being separated by a groove 16 extending lengthwise of the under surface of the foot 8. This groove 16 is of such width and depth to permit the ready unobstructed travel therethrough rearwardly from the needle N of the row 17 of back stitching produced in the 10 creation of the tufts or pile upon the fabric F.

15 This assures the free rearward feeding of the fabric F and to further prevent clogging of the cloth the heel portion of the presser foot 8 is disposed upwardly and rearwardly on a predetermined bevel, as at 18. This bevel 18 together with the distance the opening 6 extends rearwardly of the presser foot 8 results in a free and unhampered rearward feeding of the work or fabric F.

20 The portions of the working areas of the presser foot 8 at opposite sides of the groove 16 have produced therealong the parallel shallow grooves 19. These grooves 19 are of especial importance and advantage as when the presser foot 8 is lowered into working engagement with the fabric F, the portions of the fabric at opposite sides of the slot 10 and particularly immediately adjacent to the needle N are effectively prevented from being pulled inwardly toward the slot 10 as the needle passes downwardly through the fabric F or as the needle moves upwardly out from the cloth. By this means it is possible with the present machine to decorate by tufts fabric of extremely light weight and more especially when the thread or strand employed is a dyed yarn or otherwise coarse in character. To those familiar with work for which the present machine is intended it is well known that the frictional contact between the coarse thread or strand and the fabric as the 30 needle passes through the fabric has a tendency to impose strain and stress upon the fabric resulting in tearing of the fabric or the pulling of the fabric in a manner resulting in an unsatisfactory finish. While this objection does not apply when the machine is used in connection with a relatively heavy fabric, such as duck, yet it is not only important but necessary to provide a means such as these grooves 19 for holding the cloth against lateral pull with respect to the slots 35 10 when working with light weight fabric. In other words, the means as afforded by these grooves 19 hold the cloth taut across the opening 6 so as to permit the desired movements of the needle with its strand or yarn through the fabric. 45

50 It is to be stated at this time that the sewing machine intended for tufting requires no shuttle although the mechanism contains the shaft 20 which is provided in the ordinary machines for operating the shuttle. This shaft 20 is driven in a well known manner and, therefore, a detailed description and illustration of its operating means is believed to be unnecessary. It is to be stated, of course, that the shaft 20 rotates in proper time sequence with respect to the operation of the needle bar 1 and the shafts 4 and 5 in the production of the work for which the present machine is to be employed.

55 The bed plate 3 to one side of the plate 7 and preferably at the inner side, is provided with a 60 depending flange 21 to which is secured the upper end portion of a depending arm 22 of desired length. As herein disclosed, this arm 22 is held to the flange 21 by a bolt 23 freely disposed through the flange 21 but threading into the por- 65 70 75

tion of the arm 22 overlying the flange 21. By proper turning of the bolt 23 the arm 22 may be effectively clamped in desired position yet if it should be desired to adjust the arm 22 by swinging the same about the bolt 23, this can be readily accomplished by loosening the bolt.

The lower end portion of the arm 22 is enlarged to one side thereof to provide a block 24. This block has produced therethrough a bore 25 preferably substantially at right angles to the arm 22, or more particularly at right angles to the path of travel in which said arm 22 may be adjusted. Threading into the bore 25 in the block 24 is an end portion of an elongated member or bar 26 cylindrical in form and of desired length. Also threading upon this member or bar 26 at opposite sides of the block 24 and coacting therewith are the lock nuts 27. These nuts 27 provide means for effectively maintaining the member or bar 26 in its desired lengthwise adjustment with respect to the block 24 or more particularly the arm 22.

This bar or member 26 extends forwardly of the block 24 a distance to intersect the path of travel of the needle N and freely mounted upon such portion of the bar or member 26 is a bearing 28 carried by one end portion of a rock arm 29. The outer end portion of this rock arm 29 is provided with an upstanding extension 30, the rocker arm 29 and its extension 30 constituting a carrier for the arm of the looper, to be described. The bar or member 26 between the arm 22 and the bearing 28 is provided with a thrust flange 31 preferably integral therewith and against which the bearing 28 is constantly urged under the action of the expansible member 32 herein disclosed as a coil spring interposed between the bearing 28 and a head or enlargement 33 carried by the member or bar 26 outwardly of the bearing 28. This member or enlargement 33 as herein disclosed constitutes a nut threading upon the member or bar 26 whereby the tension of the member 32 may be increased or decreased as desired. As herein disclosed the expansible member 32 comprises a coil spring of requisite tension encircling the member or bar 26 with its inner end portion in direct contact with a washer 34 surrounding the bar or member 26.

Overlying the side face of the upstanding extension 30 of the rock arm 29 and the adjacent portion of the arm 29 is the lower extremity of an upstanding flat bar or arm 35. This overlying portion of the bar or arm 35 has produced therethrough a pair of aligned and longitudinally disposed slots 36 and 37. Directed through the lower slot 36 is a holding screw 38 threading into the outer portion of the rock arm 29. This screw 38 also serves as a fulcrum or pivot when it is desired to swingingly adjust the bar 35 toward or from the path of travel of the needle N for a purpose to be hereinafter more particularly referred to.

Disposed through the upper slot 37 and a curved slot 39 in the upper part of the extension 30 is a bolt 40, the free end portion of which having threaded thereon a clamping nut 41 for coaction with the extension 30 of the rock arm 29. This bolt 40 in addition to providing means for holding the bar 35 to the extension 30 also operates to effectively maintain the bar 35 in its desired selective adjustment about the bolt 38 as a fulcrum.

The upper portion of the bar 35 is provided thereacross with a groove 42 in which snugly fits an outstanding flat shank 43 carried by the looper

and knife plate 44. The base of the groove 42 at substantially its axial center is provided with an outstanding lug 45 which is received within a suitably positioned opening 46 disposed through the shank 43 of the plate 44. Bridging the groove 42 and extending across the applied shank 43 is an end portion of a holding bar 47 removably or securely held to the bar 35 in any preferred manner as generally indicated at 48. However, I do not wish to be understood as limiting myself to the particular kind of clamping means as illustrated at 48 in the accompanying drawings as it is possible to use other means with equal advantage.

Overlying the face of the bar 35 opposite to the face provided with the groove 42 is an elongated plate 49, the intermediate portion of which is pivotally connected through the medium of the bolt 50 with said bar 35 so that said plate 49 may have selective adjustment about the bolt 50 as a fulcrum as provided by the arcuate slot 51 through which is disposed the clamping bolt 52. As is clearly illustrated in Figure 7 of the drawings, the bolts 50 and 52 both thread into the bar 30 but are freely disposed through the plate 49. It is also to be further stated that the bolt 50 as well as the bolt 52 may be used to clamp the plate 49 in desired adjustment upon the bar 35. The slot 51, as illustrated in the accompanying drawings, is preferably in the lower portion of the applied plate 49 and extending outwardly and laterally from the opposite or upper end portion of the plate 49 is a pin 53 which is freely disposed through an end portion of a rigid link 54 the opposite end portion of which being pivotally connected, as at 55, with the outer end portion of the crank 56 carried by the shaft 20.

As is believed to be clearly understood by those skilled in the art to which the present invention appertains, the shaft 20 is a rock shaft operating to effect the desired throw of the crank 56 to effect an oscillation of the bar 35 about the bar or member 26 as a fulcrum a distance sufficient to effect the desired movement of the plate 44 and more particularly the looper 57 and the knife 58 with respect to the loop 59 of yarn or other thread as formed by the needle N as it passes down through the fabric F and moves upwardly.

It is to be understood that when the needle N is raised to its highest position the bar 35 has been moved to its farthest position away from the path of travel of the needle. When the needle N has completed its downward movement the bar 35 will have been moved toward the needle a distance sufficient to bring the tip of the looper 57 at a point just about to enter the loop of the thread or yarn formed by the succeeding raising or upward movement of the needle. It is for this purpose that the various adjustments hereinbefore referred to are provided as it is important and necessary that ready and convenient means to assure the assembly of the parts so that this proper positioning of the tip of the looper 57 will be assured. As the needle N raises or moves upward the loop of the strand or thread of course will be formed around the outer portion of the looper 57 the under surface of which is blunt for a desired distance in order to prevent severing or cutting of the loop until the loop has been moved rearwardly of the looper 57 a distance sufficient to allow the forward portion of the looper 57 to be free for the formation of the next succeeding loop. As the needle raises or moves upwardly during the formation of the succeeding loop the previously formed loop will be engaged by

the knife 58 formed on the plate 44 immediately to the rear of the looper 57 and sever or cut the loop whereby the desired pile is produced. It is to be noted, however, that during this looping 5 operation there is no severing of the loop being formed. This severing of the loop of course is assured by the fact that as the looper is moved forwardly in the production of the succeeding loop the fabric F will have been moved rearwardly 10 under the action of the feed dog 3 a distance sufficient to assure the proper cutting action of the knife 58.

The looper 57, as clearly illustrated in the drawings, comprises a forwardly and downwardly curved part extending from the upper portion 15 of the plate 44 and the knife 58 is comprised in the marginal portion of said part immediately adjacent to the looper 57 proper. This knife 58 is disposed on a rearward and downward curvature 20 for a distance sufficient to assure the most effective cutting action upon a loop.

It is to be particularly stated at this time that the tip portion of the looper 57 is extremely thin so as to assure its proper entrance within the 25 loop of the thread or yarn and which is particularly essential when the work is unusually fine.

Pivotedly held at a particular point upon the plate 44 by the bolt 60 is a knife blade 61, the cutting edge 62 of which is preferably straight. 30 This blade 61 is so constructed and designed to assure proper coaction of the cutting edge 62 of the blade 61 with the knife 58 upon required rocking movement being given to the blade 61. The blade 61 is also constantly urged into proper 35 working position with respect to the plate 44 by an expansible member or spring 63 herein disclosed as encircling the bolt 60 between the head thereof and the blade 61. The bolt 60 also has engaged therewith a holding nut 64.

40 The blade 61 is provided with a shank 65 having a slot or kerf 66 in which is received a pin 67 extending laterally from an arm 68 clamped into selective adjusted position by a bolt 69 extending through a longitudinally directed slot 70 45 in the arm 68 and engaged with a lug or other part 71 depending from the machine bed 3. The throw of the knife blade 61 can be readily regulated or varied as required by endwise adjustment of the arm 68.

50 It is to be particularly mentioned at this time that the mounting of the plate 44 is such that it can be readily applied or removed should it be desired to sharpen the knife 58 or if it should be desired to make a replacement. The 55 removal or application of the plate 44 is readily obtained without in any way affecting other adjustments of the machine. This in a machine of this kind is very important.

60 From the foregoing description it is thought to be obvious that a tufting machine constructed in accordance with my invention is particularly well adapted for use by reason of the convenience and facility with which it may be assembled and operated, and it will also be obvious that my 65 invention is susceptible of some change and modification without departing from the principles and spirit thereof and for this reason I do not wish to be understood as limiting myself to the precise arrangement and formation of the 70 several parts herein shown in carrying out my invention in practice except as hereinafter claimed.

I claim:

1. In a tufting machine, a work support, a reciprocatory needle to carry the yarn through the 75

work and produce loops, work feed means for coaction with the needle, supporting means including a shaft having its longitudinal axis extending across the line of work feed, an oscillatory carrier pivotally mounted upon the shaft, said carrier 5 having a generally horizontal slot, a looper including an upstanding arm, said arm being provided with a plurality of generally vertical slots, a connecting element passing through one generally vertical slot and attached to the carrier 10 and adapted to serve as a fulcrum for the arm, a bolt passing through the other generally vertical slot and through the generally horizontal slot in the carrier to permit of the vertical adjustment of the arm and also the angular adjustment 15 of the arm about the connecting element, the bolt being adapted to clamp the arm to the carrier, means to oscillate the carrier and looper to cause the looper to enter the loops, and means to sever the loops upon the looper. 20

2. In a tufting machine, a work support, a reciprocatory needle to carry the yarn through the work and produce loops, work feed means for coaction with the needle, a supporting element, a carrier, adjustable means pivotally 25 mounting the carrier upon the supporting element so that the carrier turns about an axis extending transversely of the line of work feed, the adjustable means providing for the arrangement of the carrier at different distances from 30 the supporting element, a looper including an upstanding arm, means for vertically adjustably mounting the upstanding arm upon the carrier, means to oscillate the carrier and looper to cause the looper to enter the loops, and means 35 to sever the loops upon the looper.

3. In a tufting machine, a work support, a reciprocatory needle to carry the yarn through the work and produce loops, work feed means for coaction with the needle, a relatively stationary part, an arm depending from the relatively stationary part and angularly adjustable in a plane generally parallel with the line of work feed, a substantially horizontal member extending transversely of the line of work feed 40 and longitudinally adjustably mounted upon the arm, a looper mounted upon the member to turn about the longitudinal axis of the member for swinging movement in a direction longitudinally 45 of the line of work feed toward and from the needle, means to swing the looper, and means to sever the loops upon the looper. 50

4. In a tufting machine, a work support, a reciprocatory needle to carry the yarn through the work and produce loops, work feed means for coaction with the needle, a relatively stationary part, a depending arm angularly adjustable mounted upon the relatively stationary part and shiftable in a plane generally parallel with the line of work feed, a substantially horizontal 60 member arranged transversely of the line of work and longitudinally adjustably mounted upon the lower portion of the arm, a carrier mounted upon the member to turn about the longitudinal axis of the member, a looper having an upstanding arm, means to vertically adjustably mount the arm upon the carrier, the carrier and looper swinging in a plane extending longitudinally of the line of work feed, means to swing the carrier and looper to cause the 65 looper to enter the loops, and means to sever the loops upon the looper. 70

5. In a tufting machine, a work support, a reciprocatory needle to pass the yarn through the fabric and produce loops, work feed means for 75

coaction with the needle, a supported shaft extending transversely of the line of work, a vertically swinging looper mounted upon the shaft for movement in a plane longitudinally of the line of work feed toward and from the needle, a member angularly adjustably mounted upon the looper between the upper and lower ends of the looper and having a pivot element near one end of the member, a link engaging the pivot element, 10 means to reciprocate the link, and means to sever the loops upon the looper.

6. In a tufting machine, a work support, a reciprocatory needle to carry the yarn through the work and produce loops, a reciprocatory looper 15 to enter the loops, a lever pivotally mounted between its ends upon the looper between the opposite ends of the looper and provided near one end of said lever with a pivot element, adjustable means to clamp the opposite end of the lever to the looper, a link engaging the pivot element, 20 means to reciprocate the link, and means to sever the loops upon the looper.

7. In a tufting machine, a work support, a reciprocatory needle to carry the yarn through the work and produce loops, work feed mechanism for coaction with the needle, an arm provided upon one face with a transverse groove having oppositely arranged edges, one side of the groove being open, a looper having a shank for insertion 25 within the groove, said shank having an opening, a pin attached to the arm and arranged within the groove and adapted for insertion within the opening in the shank, the pin holding the shank against longitudinal movement with relation to the arm and permitting of the free lateral movement of the shank with relation to the arm, and a member mounted upon the arm and adapted to extend across the groove to prevent the lateral movement of the shank out of the groove, said 30 member being adjustable to uncover the groove so that the shank may be removed laterally therefrom.

8. In a tufting machine, a work support, a reciprocatory needle to carry the yarn through the work and produce loops, work feed mechanism for coaction with the needle, actuating means for the work feed mechanism, a looper for movement toward and from the needle and having a depending arm, a cutter to sever the loops upon the looper, means to actuate the cutter, a reciprocatory carrier having a part arranged below the looper, cutter, and actuating means for the same, the depending arm of the looper having its lower portion arranged adjacent to said part of the carrier, 50 means for vertically adjustably mounting the lower portion of the arm upon said part, and means to move the carrier and looper as a unit and disposed above the mounting means, the arrangement being such that access may be readily had to the mounting means.

9. In a tufting machine, a work support, a reciprocatory needle to carry the yarn through the

work and produce loops, work feed mechanism for coaction with the needle, actuating means for the work feed mechanism, a looper for movement toward and from the needle and having a depending arm provided in its lower portion with a longitudinal slot, a cutter to sever the loops upon the looper, means to actuate the cutter, a reciprocatory carrier having a part arranged below the work feed mechanism, looper, cutter, and actuating means for the same, the lower portion of the arm having the longitudinal slot being arranged upon said part, an adjustable clamping element secured to said part and arranged within the longitudinal slot to permit of the vertical adjustment of the arm with relation to said part, 15 means to move the carrier and looper as a unit and arranged at a different elevation from the clamping element, the arrangement being such that access may be readily had to the clamping element.

10. In a tufting machine, a work support, a reciprocatory needle to carry the yarn through the work and produce loops, work feed mechanism for coaction with the needle, an element having a longitudinal axis, means to support the 25 element below the work support, a swinging carrier mounted upon the element to turn about the longitudinal axis of the element, a looper adapted to move across the path of travel of the needle and having a long arm extending downwardly below the longitudinal axis of the element, the arm being provided near its lower end with a longitudinal slot, an adjustable clamping element secured to the carrier and arranged within the longitudinal slot, the arm being adapted to be raised 30 and lowered with respect to the carrier and the adjustable element serving to clamp the arm to the carrier in the selected adjusted position, means to swing the carrier and looper as a unit, and means to sever the loops upon the looper. 40

11. In a tufting machine, a work support, a reciprocatory needle to carry the yarn through the work support and to produce loops, work feed means for coaction with the needle, a reciprocatory carrier, a looper including a generally vertical arm, said arm and carrier having engaging parts, one engaging part having generally vertical slots and the other engaging part having a generally horizontal slot, a connecting element carried by one engaging part and extending through one generally vertical slot, a second connecting element arranged within the other generally vertical slot and adapted for movement within the generally horizontal slot, the arrangement being such that the arm of the looper may be angularly and vertically adjusted with respect to the carrier and clamped thereto in the selected adjusted position, means to reciprocate the carrier and looper to cause the looper to enter the loops, and means to sever the loops upon the 50 looper. 55

GLENN LOOPER.
